UNITED STATES PATENT OFFICE.

JAMES MILNOR HICKS, OF SUMMIT, NEW JERSEY, ASSIGNOR TO AUTO STOPPER COMPANY, OF NEW YORK, N. Y.

SEALING-CAP CONTROLLER.

949,478.

Specification of Letters Patent. Patented Feb. 15, 1910.

Application filed March 2, 1909. Serial No. 480,930.

To all whom it may concern:

Be it known that I, JAMES MILNOR HICKS, a citizen of the United States, residing at Summit, Union county, New Jersey, have 5 invented certain new and useful Improvements in Sealing-Cap Controllers, of which the following is a specification.

My invention relates to means for centering and controlling sealing caps in capping 10 tools.

The object of my invention is to provide means for absolutely controlling the position of a sealing cap in a capping tool during the whole operation of securing the cap 15 over a vessel mouth and bead and to this end my invention consists in certain elements in combination fully set forth and claimed in the following specification.

In order that those skilled in the art to 20 which my invention appertains may understand, construct and use my invention, I will proceed to describe it referring to the accompanying drawings, forming part of this specification in which—

25 Figure 1. shows a longitudinal central section of a capping tool provided with my invention; the spindle of the cap controller in its normal position with the barrel of a sealing cap inserted within the cup of the controller, ready to be applied to a vessel, the cap is shown as held in the capping tool by the rim or flange of the cap which is more or less elastic. Fig. 2. shows the same 30 in position after the cap has been applied to the vessel. Fig. 3. shows a bottom view of the capping tool and controller without the cap and bottle. Fig. 4. shows a top view of the controller.

35 A. shows a bottle having a bead A¹. B. shows a hollow cylindrical capping tool.

C. shows a hollow cylindrical controller fitting the diameter of the hollow G of the capping tool.

40 D. shows a spindle which extends from the top of the center of the controller C up into a bore N of the body of the capping tool B.

E. shows a slot crosswise of spindle D. F. shows a pin passed through the body of tool B, and through the slot E in the spindle D. This slot E and pin F control the downward throw of the controller C as shown in Fig. 1.

45 G. shows the hollow of capping tool B.

H. shows the lower part of tool B bored out to a size about equal to the diameter of the cap flange to be used, but so that the spring of the flange in entering this bore H will hold the cap by its frictional contact with the sides of the bore H, and under the shoulder P where bores H and G join.

I. shows a crimped flange sealing cap having a smooth barrel and crown.

J. shows the inner walls of the hollow G 50 of tool B.

K. shows the cork lining in the cap I.

L. shows a spring pressing on spindle D located in its bore N of the tool B.

M. shows the screw by which the tool is 70 to be attached to a capping machine head.

N. shows the bore in tool B in which spindle D works.

O. shows the hollow of controller C of a diameter to fit the barrel of the cap being 75 used.

P. shows the shoulder at the bottom of the hollow G and above the bore H, at the point where the two join.

The hollow G of the tool B is of larger 80 diameter than the cap I which is being used and the cap fits the inner wall of controller C and controller C fits the hollow of tool B, so that the cap I is centered in the tool and held in controller C. The wall of controller C extends only partially to the depth of the cap barrel I, so that the controller walls do not interfere with the expansion of the cap barrel while the cap and bottle bead are brought forcibly together in capping. The cap is expanded in passing the extreme diameter of the cap bead. The controller recedes into the hollow of tool B and the cap controlled at all times by the controller C, passes into the hollow of tool B. 95 The shoulder P at the bottom of the wall J engages the flange of the cap I and compresses it inward until its exterior circumference passes into the hollow G of tool B, thus forcing the crimps under the vessel bead A¹, as shown in Fig. 2, and locking the cap to the vessel in perfectly true alinement.

Having now fully described my invention and the manner in which I have embodied it, what I claim as new and as my invention and desire to secure by Letters Patent is—

The combination with a cup shaped capping tool, of an implement for centering and controlling sealing caps, while being applied to vessels, which consists of a cup shaped cylind-

drical controller which fits the barrel of the cap, and is arranged to fit and have vertical movement in the internal bore of a cup shaped capping tool; a spring located within 5 the capping tool which presses upon the cup shaped cylindrical controller; and a stop arranged within said capping tool to limit the downward throw of said cup shaped cylindrical controller, all constructed, and arranged to operate to embrace, center and 10 control the position and movement of a

sealing cap, within the capping tool at all times during the capping operation, substantially as specified.

In testimony whereof, I have signed my 15 name to this specification in the presence of two subscribing witnesses, this 1st day of March 1909.

JAMES MILNOR HICKS.
